EDGING ROLLER

Filed Sept. 20, 1948

UNITED STATES PATENT OFFICE

2,663,892

EDGING ROLLER

Albert W. Schaefer, Los Angeles, Calif.

Application September 20, 1948, Serial No. 50,216

4 Claims. (Cl. 15—230)

1

This invention relates to a paint applicator of the roller type. More particularly, it relates to a paint applicator of the roller type which is adapted to apply paint along an edge, as along the edge of a molding or a door frame.

Roller type applicators comprising a roller rotatably mounted on a shaft and having a napped sleeve of suitable paint absorbent material secured to the roller, are advantageous because of cheapness, ease of application of the paint, etc. However, such paint applicators suffer a disadvantage in application of paint along the edge of a wall or the like, for example, where it is required to apply paint along the edge of a molding or door frame without applying paint to the adjacent structure.

It is an object of the present invention to provide a roller type paint applicator which is adapted to apply paint along an edge or border.

It is a further object of the invention to provide a roller type paint applicator adapted to edging, which is simple in design and inexpensive to construct, and which embodies a removable napped sleeve which may be easily removed and replaced by another napped sleeve.

These and other objects of the invention will be apparent from the ensuing description and the appended claims.

One form which the invention may assume is exemplified in the following description and illustrated by way of example in the accompanying drawings, in which:

Fig. 1 is a view, partly in elevation and partly in section, of the paint applicator of the invention.

Fig. 2 is a perspective view of the napped sleeve used with the paint applicator.

Fig. 3 is a perspective view showing the manner in which the applicator may be used.

Referring now to the drawings, a bent handle 1 is provided having at one end a hand grip 2 and at its other end a shaft portion 3. The shaft 3 is of smaller diameter than the adjacent handle portion to provide a shoulder 4 and it is threaded at its outer end at 5. Mounted upon and secured to the shaft by means of washers 10 and a nut 11 is a disc-shaped roller 12, such roller being provided with a transverse bore 13 of a diameter to provide a close fit with the shaft 3 but to permit the roller to rotate freely thereon. The roller 12 may be made of any suitable material but preferably it is made of a transparent plastic material such as Lucite. The roller 12 is provided with a peripheral groove 14 defined at

2

its outer edge, by a beveled flange 15 and at its inner edge by a flange 15a of considerably greater diameter than the flange 15.

A removable napped sleeve 16 is provided having a core or backing 17 of any suitable flexible material, such as leather, and with an outer nap material 18 of wool or other suitable paint absorbent material. The core 17 may be provided separately, cut to strip form and provided 10 with a separate nap material 18, which is affixed to the core in any suitable manner, as by an adhesive. Preferably, however, the napped sleeve 16 is in the form of an animal pelt, such as a sheep pelt, cut to strip form, the core 17 being provided by the hide of the animal and the nap material 18 by its hair or wool. The ends of the napped sleeve are brought together to form a seam at 19 and the adjacent edges are secured together by any suitable means such 20 as staples 20, the staples being inserted from the interior of the core so that their free ends are located on the exterior surface of the core. Seating staples 21 are also provided, as shown, being disposed circumferentially and nearer one 25 edge of the core and being inserted in the same manner as the seam staples 20.

The napped sleeve thus provided is readily mounted on the roller 12 and, as will be seen from Fig. 1, the seating staples 21 are seated in the peripheral groove 14, thus serving to retain the napped sleeve in place but, nevertheless, allowing ready removal of the same as by inserting a finger and pulling the nap off of the roller.

Referring now to Fig. 3, intersecting surfaces 30 and 31 are shown, forming a corner, and it is desired to apply paint only to the surface 30. This is accomplished, as shown, by holding the applicator at about a 45° angle, midway between the surfaces 30 and 31, and with the edging flange 15a adjacent the surface 31 and the beveled flange 15 adjacent surface 30. The napped sleeve 16 extends outwardly of the beveled edge 15 to provide paint applying material adjacent said beveled edge 15. The applicator is run along the corner while held in this position. Paint is applied to but not beyond the intersection or boundary 32 between the surfaces 30 and 31.

A paint applicator is thus provided which is simple in design, inexpensive to manufacture, easy to assemble and disassemble, and efficient for the purposes described. The napped sleeve itself is advantageous for the same reasons and because it is easily mounted and dismounted.

While I have shown the preferred form of my

invention, it is to be understood that various changes may be made in its construction by those skilled in the art without departing from the spirit of the invention as defined in the appended claims.

Having thus described my invention, what I claim and desire to obtain by Letters Patent is:

1. A paint applicator comprising a frame member including a handle portion and a shouldered shaft portion disposed transversely to said handle portion, a sleeve supporting disc rotatably mounted on the shaft portion adjacent the shoulder on the shaft portion, a nut threadedly received on the end of the shaft portion for retaining said disc on said shaft portion, said disc having a flange disposed on the side thereof adjacent the shoulder, a flexible napped sleeve receivable on the disc against the flange, said flange terminating short of the periphery of the napped sleeve, said sleeve having inwardly extending protuberances thereon, said protuberances being separate and individually connected to the sleeve and being spaced from one another so as not to impair the flexibility of the sleeve, said disc having an abutting formation disposed outwardly of and in abutting relationship with the protuberances on the sleeve to releasably retain said sleeve on said disc.

2. A paint applicator comprising a frame member including a handle portion and a shouldered shaft portion disposed transversely to said handle portion, a sleeve supporting disc rotatably mounted on the shaft portion adjacent the shoulder on the shaft portion, a nut threadedly received on the end of the shaft portion for retaining said disc on said shaft portion, said disc having a flange disposed on the side thereof adjacent the shoulder, a flexible napped sleeve receivable on the disc against the flange, said flange terminating short of the periphery of the napped sleeve, said sleeve having inwardly extending protuberances thereon, said protuberances being separate and individually connected to the sleeve and being spaced from one another so as not to impair the flexibility of the sleeve, said disc having another flange of a height approximately equal to the height of the protuberances on the sleeve and disposed outwardly of and in abutting relation with the protuberances on the sleeve to releasably retain said sleeve on said disc.

3. A paint applicator comprising a frame member including a handle portion and a shaft, a sleeve supporting disc rotatably mounted on said

shaft, said disc having a flange disposed on the side thereof adjacent the handle, a flexible napped sleeve receivable on the disc against the flange, said flange terminating short of the periphery of the napped sleeve, said sleeve having separate inwardly extending protuberances thereon, said protuberances being individually connected to the sleeve and being spaced from one another so as not to impair flexibility of the sleeve, said disc having an abutting formation disposed outwardly of and in abutting relationship with said protuberances on the sleeve to releasably retain said sleeve on the disc.

4. A paint applicator comprising a frame member including a handle portion and a shaft, a sleeve supporting disc rotatably mounted on said shaft, said disc having a flange disposed on the side thereof adjacent the handle, a flexible napped sleeve receivable on the disc against said flange, said flange terminating short of the periphery of the napped sleeve, said sleeve having separate inwardly extending protuberances thereon, said protuberances being individually connected to the sleeve and being spaced from one another so as not to impair the flexibility of the sleeve, said disc having another flange of a height approximately equal to the protuberances of the sleeve and disposed outwardly of and in abutting relationship with the protuberances on the sleeve to releasably retain said sleeve on said disc.

ALBERT W. SCHAEFER.
